UNITED STATES PATENT OFFICE

MILTON L. DODGE, OF NEWBURYPORT, MASSACHUSETTS

METHOD OF FORMING THE HEEL PORTIONS OF SHOES

Application filed October 25, 1930. Serial No. 491,103.

In the formation of the heel portions of shoes, more particularly when wood heels are to be used, it is of great importance in the appearance of the shoe to prevent any gapping or grinning of the heel margin and the shoe upper, or any marked break in the contour line of the upper and the heel surface. It has been usual, therefore, for the shoe-maker to attempt by pounding on the heel portion of the upper when it is on the last to bring the upper into proper place with reference to the heel. This, however, is troublesome and requires care, skill and time and is often very imperfectly done. By the use of a counter stiffener having a marginal outwardly extending rib in its attaching flange, as shown and described in my Patent No. 1,430,158, dated September 26, 1922, the necessity of pounding up the heel portion may be either eliminated entirely or very much reduced, but unless care is exercised during the bed lasting operation, the pressure between the shoe and the heel wipers of the bed lasting machine may flatten this bed to such an extent that its full advantage may not be realized in practice.

In accordance with the present invention the shoe is so made that where a beaded flange counter stiffener is employed, the bead is not crushed down during bed lasting and where a flat flange in the counter is initially employed, the subsequent operations act to form a bead-simulating portion which to some extent at least facilitates the fitting of the heel margin.

For a more complete understanding of this invention, reference may be had to the accompanying drawing in which

Figure 1 is a perspective of an innersole treated in accordance with one embodiment of this invention.

Figure 2 is a section on line 2-2 of Figure 1.

Figure 3 is a somewhat diagrammatic section through the heel portion of a shoe employing the innersole of Figures 1 and 2 and showing in dotted lines the position of a wood heel.

Figure 4 is a fragmentary perspective of

the heel portion of an innersole showing a modified construction.

Figure 5 is a bottom plan of a pair of heel wipers for a bed laster, the wipers being formed in accordance with this invention.

Figure 6 is a somewhat diagrammatic section through the wipers and heel portion of a shoe being bed lasted, the shoe being pressed against the wipers.

Figure 7 is a view similar to Figure 6 but illustrating somewhat diagrammatically the action of the wipers as shown in Figure 5 when the shoe is provided with a counter initially having a substantially flat securing flange, together with an innersole of uniform thickness from side to side.

Referring to Figure 1, at 1 is shown an innersole to the outer face of which at its margin is secured a strip 2 which forms a marginal bead therefor extending outwardly beyond the level of the innersole. Instead of forming the bead in this manner the outer face of the innersole may be recessed inwardly of its margin, as shown in Figures 4 at 3, thus leaving a marginal bead portion 4 of the full thickness of the innersole.

This innersole may be tacked to the last in the usual manner, the bead extending outwardly, and the upper materials lasted thereover, as shown in Figure 3. The upper materials will commonly include the attaching flange 5 of a counter stiffener 6 placed between the upper 7 and the lining 8. Preferably the counter flange 5 is provided with a marginal outwardly extending bead as 10, as illustrated in my Patent No. 1,430,158, hereinbefore mentioned, the bead 10 extending over the marginal bead of the innersole which forms a filler therefor preventing the upper materials from being crowded down and the flange bead 10 being crushed or flattened during the lasting operations.

To further minimize the possibility of this bead being crushed, it is preferable to employ a special construction of heel wipers on the bed lasting machine by which the heel seat is commonly formed. Such wipers are illustrated in Figure 5. As therein

shown the wipers 15 are arranged in a pair pivoted together at 16 so that they can be brought in over the outer edges of the innersole and wipe the upper materials there-over as is well known in the art. These wipers may be of usual construction, except that adjacent to their inner margins they are provided with recesses 17 extending therealong parallel to the inner margins and 10 in the faces of the wipers with which the shoe is engaged. Thus as the wipers are moved inwardly the inner edge portions 18 thereof pass over the innersole and when fully wiped in they are positioned inwardly 15 of the beads on the innersole and the counter flange. Then when the partially lasted shoe is pressed upwardly against the wipers in accordance with the usual method, and as shown by the arrow *a* in Figure 6, the 20 upper materials are pressed strongly against the innersole inwardly of the marginal bead, but at the margin the pressure is reduced. This permits the upper materials to bulge outwardly beyond the level of those portions 25 inwardly of the margin, to form a rounded seat portion 20 against which the marginal edge 21 of a wood heel may be firmly engaged without the possibility of grinning or separation and with the shoe surfaces substantially continuous along the upper and over the outer surface of the heel. In case a 30 counter with an initially flat flange is employed in connection with an innersole having a marginal bead, the pressure of the 35 wipers on the upper materials tends to form a bead in the counter flange so that a similar final result in the shaping of the heel seat of the shoe is produced, although this may not be effected to as great an extent as 40 though the bead were initially formed in the counter flange.

It is also possible by the use of the wipers, as shown in Figure 5, to produce somewhat the same conformation of the shoe heel seat 45 even when using an innersole of uniform thickness from side to side at its heel portion and using a counter having a flat flange, this being shown in Figure 7. The pressure exerted by the inner edges 18 of the wipers 50 is then localized inwardly of the margin of the innersole, compressing the upper materials inwardly of this margin and permitting them to bulge upwardly toward the innersole margin so that a beaded effect at the 55 margin of the heel seat is produced, although usually less pronounced than where the innersole or the counter flange, or both, are provided with the beaded constructions. However, even this less pronounced bead 60 aids materially in forming a close joint with the wood heel.

When the tacks as shown at 22 in Figure 3 are driven in to secure the lasted upper margins they are driven through these margins inwardly of the beaded portion, the

pressure of the tacks being driven and clinched tending further to depress the portions within the bead and to accentuate the prominence of the bead.

From the foregoing description of certain 70 embodiments of this invention, it should be evident to those skilled in the art that various changes and modifications might be made without departing from the spirit or scope of this invention as defined by the 75 appended claims.

I claim:

1. The steps in the manufacture of shoes, which comprise wiping in the upper materials over the heel end of the shoe and 80 while under wiping pressure pressing the upper materials against the face of a sole member inwardly of the margin of said member to permit the upper materials of said margin to extend beyond the level of 85 the pressed portions and to form a seat for the engagement of the marginal edge of a wood heel.

2. In the manufacture of shoes, those 90 steps which comprise forming a marginal outwardly extending bead on the heel portion of an innersole, and lasting in and conforming the upper materials over said bead and to the face of said innersole inwardly of 95 said bead, whereby the upper materials at the margin of said innersole project beyond their position inwardly thereof and form a seat for engagement by the marginal edge of a wood heel.

3. In the manufacture of shoes, those 100 steps which comprise wiping in the upper materials including the sole attaching flange of a counter stiffener over the heel end of the shoe and while under wiping pressure pressing said upper materials including said flange against the face of a sole member inwardly of the margin of said member to permit said upper materials to 105 extend beyond the level of the pressed portions and form a seat for engagement by the marginal edge of a wood heel.

4. In the manufacture of shoes, those 110 steps which comprise fixing a strip to the marginal portion of an innersole at its heel end to form an outwardly extending bead 115 thereon, and lasting in and conforming the margin of the upper materials including a counter stiffener attaching flange to said bead and to the face of the innersole inwardly of said bead to form a marginal 120 bulge in said material serving as a seat to receive the marginal edge of a wood heel.

5. In the manufacture of shoes, those steps 125 which comprise removing the outer face of an innersole inwardly of its margin at the heel end to form a marginal outwardly extending bead, and lasting in and conforming the margin of the upper materials including a counter stiffener attaching flange 130 to said bead and to the face of the inner-

sole inwardly of said bead to form a marginal bulge in said material serving as a seat to receive the marginal edge of a wood heel.

5 6. The steps in the manufacture of shoes, which comprise wiping in the upper materials over the heel end of the shoe and while under wiping pressure pressing the upper materials against the face of a sole member inwardly of the margin of said member to permit the upper materials of said margin to extend beyond the level of the pressed portions and to form a seat for the engagement of the marginal edge of a wood heel, 10 and then tacking said upper materials to the sole member inwardly of said bead.

15 7. In the manufacture of shoes, those steps which comprise lasting over the upper materials at the heel end of the shoe over a marginal outwardly extending bead on a sole member, then clinching fasteners through said materials and sole member inwardly of said bead and securing a heel in position with a margin bearing on said 20 upper materials at said bead.

25 8. A shoe having a sole member provided with a thickened edge forming a marginal outwardly extending bead at its heel portion, upper materials extending over said bead and secured to said sole member inwardly of said bead and a heel having its margin bearing on said upper materials of said bead.

30 In testimony whereof I have affixed my
35 signature.
